UNITED STATES PATENT OFFICE.

THOMAS CLARENCE HEISEY, OF NEWARK, OHIO, ASSIGNOR TO A. H. HEISEY & COMPANY, OF NEWARK, OHIO, A PARTNERSHIP.

DESIGN FOR COMBINATION SALT AND PEPPER SHAKER.

Application filed April 15, 1927. Serial No. 21,608. Term of patent 14 years.

To all whom it may concern:

Be it known that I, THOMAS CLARENCE HEISEY, a citizen of the United States, residing at Newark, in the county of Licking and State of Ohio, have invented a new, original, and ornamental Design for Combination Salt and Pepper Shaker, of which the following is the specification, reference being had to the accompanying drawing, forming a part hereof.

The figure is a side elevation of a combination salt and pepper shaker, showing my new design.

I claim:

The ornamental design for a combination salt and pepper shaker, as shown.

THOMAS CLARENCE HEISEY.
